UNITED STATES PATENT OFFICE.

JAMES L. KERSHAW, OF CLEVELAND, OHIO.

SECTIONAL BOOKCASE.

No. 863,286.

Specification of Letters Patent.

Patented Aug. 13, 1907.

Application filed July 21, 1905. Serial No. 270,723.

To all whom it may concern:

Be it known that I, JAMES L. KERSHAW, a citizen of the United States, and a resident of Cleveland, county of Cuyahoga, State of Ohio, have invented 5 certain new and useful Improvements in Sectional Bookcases, of which I hereby declare the following to be a full, clear, and exact description, such as will enable others skilled in the art to which it appertains to make and use the same.

10 The invention consists in the employment of equalizing levers pivoted upon the case adjacent to the plane of the door, when the door is withdrawn into the case. These levers have their fulcrum or pivotal points on a common line, and their inner extremities 15 extend upon opposite sides of that line.

To cause a simultaneous and strictly coincident movement of the two levers in the same direction, their inner ends are connected by a short link which crosses this center line, the effect of such an arrangement is to move the inner ends in short intersecting arcs, and for a short distance they move nearly in the same direction, while the outer ends move in larger arcs, and the outer extremities remain for a certain 20 distance in a line parallel to the center line of the fulcrum points. These outer extremities are secured to the edges of the door by means of connecting links, whereby the smooth parallel movement of the outer extremities of the levers is communicated to the door, both when the door is pulled out and when it is pushed 25 into the case.

30 Means for causing the door, to withdraw automatically within the case when it is raised to the horizontal position also form an element of this invention.

The invention further consists in the combination 35 and arrangement of parts, as hereinafter described, shown in the accompanying drawings, and specifically pointed out in the claims.

In the accompanying drawings Figure 1 is a plan view of one section of a sectional book case, showing 40 the edge of the door, which is closed in front of the case, and showing the equalizing levers pivoted upon a cross bar of the case; Fig. 2 is a plan view of the same showing the door raised to the horizontal position and withdrawn into the case; Fig. 3 is a broken perspective 45 view of one of the levers, pivoted upon the bar shown in Fig. 1 and showing the link connecting the end of the lever with the door and the position of the spring which serves to withdraw the door into the case when raised to a horizontal position.

50 In these views 1 is the case provided with vertical side pieces 2 in which are rabbeted the shoulders 3 upon which the door D rests when withdrawn within the case; 4 is a bar on the upper edges of the case, upon which the levers 5 are fulcrumed at 6 so that they lie 55 above the door when it is horizontally withdrawn into the case, the books when in the case being below

the door. The inner or short arms 7 of the levers extend on opposite sides of a line connecting the fulcrum points 6, and a link 8 connects their extremities. The outer extremities of the long arms are turned at right angles to the arms at 9 so as to directly engage and push upon the inner edge of the door when it is in the horizontal position. However this is not absolutely essential provided the connecting means with the door is sufficiently positive. Links 10 connect these 65 extremities with hooks 11 on the inner face of the door near its inner or upper edge and located preferably at the pivotal points or projections 12 or in line therewith, so that the tension of the springs 14 will have no effect to open or close the door, when the door is 70 in the vertical position.

The movement of the levers is not great, as will be seen by referring to the figures, where, the extreme limits of movement are shown, and it is necessary that an exact proportion should be observed between the 75 lengths of the long and short arms, otherwise the device will not be operative. The proportion given is about $\frac{1}{3}$ of the length of the lever. I do not claim however, the exact proportions since a difference in construction might necessitate a difference in proportion 80 of the various parts. The short and long arms are also joined at an angle as shown, so as to obtain room between them for the link and to give length to the link.

In use the movement of one lever is exactly duplicated in the other lever, so that it is quite impossible 85 for the two ends of the door to move otherwise than exactly alike. For instance, if the door is pulled from one corner the link on that side will compel the lever on that side to follow the door, and the levers being connected for simultaneous movement the opposite lever 90 will push upon the opposite end of the door with equal force so that the two ends must move parallel to the case.

In Fig. 3 a view is shown of one lever having a downwardly turned end to engage the edge of the door. To 95 provide means for automatically withdrawing the door in the case, a coiled spring 14 is inserted in the bar 4 and is provided with one end 15 inserted in the lever and another extremity 16 inserted in the wood work, thus providing power by means of which the door is 100 automatically withdrawn into the case as soon as it is raised to the horizontal position. The coiled portion of this spring is wholly inclosed within the bar and one extremity is inserted in a slot 17 in the bar, the other being attached to the lever. This is the only practical 105 way in which a spring can be used to withdraw the door since there is otherwise no room for a sufficient number of coils to operate the door all the way back to the rear of the case.

I am aware that previous inventors have provided a 110 sliding door with various loosely arranged levers, to approximate a parallel movement and that a multi-

plicity of levers have been employed to operate against gravity to provide a parallel movement. But such is not of the spirit of the invention. I believe, however, that I am the first to provide the sliding and pivoted door of a sectional book case with separated equalizing levers having fulcrum points spaced apart from each other and having their inner extremities turned on opposite sides of the line connecting their fulcrum points, and having these arms connected by a link. The peculiar efficiency and practicability of this device I believe to be new for this purpose.

The pivotal points upon which the doors swing are the natural and convenient positions for attachment of the springs, so that the springs will act freely to withdraw the door when it is in the horizontal position but will not have any effect to open or close the door when it is hanging in the vertical position. When no springs are employed, it is not important that the links or other flexible attachments be attached to the door at its pivotal points or to the inner face of the door, that however is the preferable position of the points of attachment.

Having described the invention what I claim as new and desire to secure by Letters Patent is:

25 1. In a bookcase section, the combination with the sides and a connecting cross bar and a door adapted to slide horizontally within the section, of equalizing levers separately fulcrumed intermediate their ends upon said cross-bar, the inner or short arms of the levers projecting respectively on each side of a line connecting the fulcrum points, a link pivotally connecting the outer extremities of the short arms, and links connecting the outer extremities of the long arms of the levers with the door, substantially as described.

2. In a bookcase section, the combination with the sides and a connecting cross bar, and a door adapted to slide horizontally within the section and to hang pivotally in the front of the section when drawn out, of equalizing levers separately fulcrumed intermediate their ends upon said cross bar, the inner or short arms of the levers projecting respectively on each side of a line connecting the fulcrum points, a link pivotally connecting the outer extremities of the short arms, and links connecting the outer extremities of the long arms of the levers with the inner face of the door, and springs secured to said bar and severally engaging said levers, substantially as described.

3. In a book case section the combination with the sides and connecting cross bar and a drop door adapted to slide horizontally within the section, and to hang vertically therein upon pivotal supports when drawn out, of equalizing levers separately fulcrumed upon said cross bar intermediate of their ends, and turned downwardly at their outer ends, links connecting said downwardly turned outer ends with the inner edge of the door in line with said pivotal points of support, and means for coördinating the movements of said levers about their pivots, substantially as described.

4. In a book-case section having a top board, the combination, with the movable door, of two spring-actuated levers pivoted to the under side of the top board, said levers having their inner ends curved away from each other and their outer ends bent downward, a link pivotally connected at its ends respectively with the curved inner ends of said levers, and flexible connections between the outer down-turned ends of said levers and said door near its upper corners, substantially as specified.

In testimony whereof I hereunto set my hand this 19th day of July 1905.

JAMES L. KERSHAW.
